UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

CUTTER FOR SHEET MATERIAL.

Application filed April 16, 1924. Serial No. 706,843.

To all whom it may concern:

Be it known that I, JOHN R. GAMMETER, a citizen of the United States, residing at Akron, in the county of Summit and State of Ohio, have invented a certain new and useful Cutter for Sheet Material, of which the following is a specification.

This invention relates to rotary cutters, and more particularly to flexible knives 10 adapted to be wound helically upon the surface of a drum, comprising the cutting elements of a rotary bias-cutter for tire fabric, for example, the present invention being an improvement upon those of my copending 15 applications Serial No. 474,820, filed June 2, 1921, and Serial No. 563,570, filed May 25, 1922.

Knives heretofore used with rotary cutters of the character described have been 20 subject to frequent and annoying breakage, due in part to their relatively large section and stiffness which makes it difficult to obtain uniform temper throughout their length. To a larger degree however, said 25 breakage has been due to the fact that the knives, which are mounted upon a yielding support, have been rigidly anchored at their respective ends and the hardened platen roll, which presses the work against 30 the knives, bears against said knives in a rolling action progressively from one end to the other and causes the knife to buckle as the point of contact approaches its rigid anchorage.

35 The chief object of my invention is to provide a rotary cutter with efficient and durable cutting knives. A more specific object is to avoid buckling and consequent breakage of such knives.

40 Of the accompanying drawings:

Fig. 1 is an elevation of a rotary cutting drum and associated parts, embodying a preferred form of my invention, and the work therein.

45 Fig. 2 is a section on line 2—2 of Fig. 1.

Fig. 3 is an enlarged elevation of one of the knife-anchoring members and adjacent parts, partly broken away and sectioned.

50 Fig. 4 is a plan view of the parts shown in Fig. 3.

Fig. 5 is a section, on a large scale, on line 5—5 of Fig. 3.

Fig. 6 is a section, on a large scale, on line 6—6 of Fig. 4.

55 Referring to the drawings, 10 is a rotat-

able, cylindrical drum upon which are helically wound a plurality of thin, flexible metal knives 11, 11, and 12 is a hardened metal roll against which the knives 11 are adapted to cut a fabric strip 13 which constitutes the work, the latter passing partly around said roll to the cutting position. Guide rolls 14, 15 are positioned adjacent and parallel to the drum 10, over which passes a liner 16, so guided by said rolls as 60 to pass partly around the drum, as shown, to hold against the drum the bias-cut strips of fabric, cut by the knives 11 and carry them from the drum in orderly relation. Suitable means, (not shown) are provided 65 for driving the several rotary members, the drum 10 and hardened roll 12 being driven at the same peripheral speed.

The knife 11 consists of a thin strip of tempered metal such as spring steel, and is 70 mounted edge-wise in a slot in a metal support or holder 17, with a sufficiently loose fit to permit relative longitudinal movement of the knife. The holder 17 preferably is square in cross-section, the slot there- 75 ing being diagonally disposed. The holder is seated in a V-groove formed in the outer surface of a rectangular strip of resilient rubber 18, the latter being seated in a helical groove 19 of corresponding shape formed in 80 the surface of the drum 10, and constituting a yielding backing for the knife.

The backing strip 18 is laterally reinforced by a sinuously looped wire 20 imbedded and vulcanized within it, the sinuous 90 form of the wire permitting the free bending of the strip to conform it to the helical groove 19 of the drum. The backing strips 18 are retained in their respective slots 19, preferably under substantial compression, 95 by plates 21, 21 screwed to the face of the drum 10 and overlapping to margins of said strips, the strips thus being adapted to offer sufficient resistance to force the knives through the work, although sufficiently 100 yielding to insure proper contact of all parts of the knives with the hardened roll 12. The plates 21 also are adapted to prevent longitudinal creeping of the strips 18.

The knives 11 and knife holders 17 are 105 separately fastened at their respective ends in common anchor-brackets 22, 22, the latter being secured to the periphery of the drum 10, on its end portions, 10^a, 10^a, which are of reduced diameter, to provide clear- 110

- ance between said brackets and the platen roll 12, and to permit a substantially straight pull upon the knives and holders. The end of the holder 17 is mounted in a recess in an anchor bolt 23, being secured therein by a transverse pin 24, each anchor bolt extending through an aperture in its respective bracket 22 and adjustably secured by a nut 25 at the opposite side thereof.
- 10 The anchor bolt 23 is formed with a radial slot 26 extending into its holder-receiving recess, to accommodate the knife 11, which is bent angularly in its own plane to separate it from the holder 17 so that it may be separately anchored. The front end of the anchor bolt 23 is threaded to receive a collar 27 which fits closely about the knife and its holder in front of the anchor-bolt, to prevent separation of the same beyond this point. The collar 27 has a radial slot 27^a, which, when aligned with the slot 26 of the anchor bolt permits the insertion or removal of the knife 11 without removal of said collar from the anchor bolt.
- 15 The ends of the knives 11 are secured in the heads of respective anchor bolts 28, each of which extends through an obliquely disposed aperture in the anchor-bracket 22 above the anchor bolt 23. The head of the anchor bolt 28 is formed with a recess 28^a open to its end face through a narrow slot 28^b, accommodating the knife, and the end portion of the knife 11, within said recess, is looped around a removable wedge 29 therein, adapted to anchor the knife by wedging it against the walls of the recess. Accidental displacement of the wedge 29 is prevented by a cotter pin 29^a mounted in the bolt head and traversing the recess above said wedge.
- 20 The anchor bolts 28 at one end of the drum 10 (to the right as viewed in Fig. 1) are anchored to the respective brackets 22 by nuts 30 threaded onto their outer ends, this being the end of the drum at which the knives 11 first come into contact with the roll 12 during the operation of the machine. At the other end of the drum the stem of each anchor bolt 28 is surrounded by a helical compression spring 31, interposed between abutting retaining nuts 32, 32 on said stem and the adjacent face of the anchor bracket.
- 25 In the operation of the rotary cutter, the successive knives 11 contact the hard roll 12 first at their ends which are rigidly anchored, and the rolling contact progresses toward their yieldingly anchored ends, the drum being of such size and the knives being disposed at such angle thereon that the trailing end of said knife passes out of contact with the platen roll before its leading end again contacts therewith. The knives 11 being slidable within their respective holders 17, buckling of the knife is avoided,

the springs 31 maintaining tension upon the knives while the latter creep longitudinally in their respective slots under the force of the platen roll, and said springs permit retraction of the knives after they pass out 70 of engagement with the platen roll.

My invention permits the use of a knife of such thinness that when positioned edge-wise it is sufficiently sharp to sever the work, so that sharpening of the knife is 75 not required. Such knives are capable of more uniform tempering than those of larger cross-section, so that they may be made more durable, and expense is saved both because breakage is reduced and because the knives are inexpensive. The simple arrangement for mounting the knives results in a saving of time and labor in replacing one that has broken.

My invention may be modified within its 85 scope and I do not limit my claims wholly to the exact construction shown.

I claim:

1. In a cutter for sheet material, the combination of a knife-holding member formed with a knife-receiving slot of substantially uniform width throughout its knife-receiving region, an upstanding, strip-metal knife of substantially uniform thickness slidably mounted in said slot, means for so holding the knife in the slot as to permit its elongation and contraction therein, and means for forcing the work against said knife in a progressive cutting action. 90

2. In a cutter for sheet material, the combination of a knife-holding member, a flexible knife mounted thereon, yielding means for holding said knife under longitudinal tension, and roller means adapted to run upon the work for forcing the latter against 100 said knife in a progressive cutting action. 105

3. In a cutter for sheet material, the combination of a knife-holding member formed with a knife-receiving slot having substantially uniform width throughout its knife-receiving region, an upstanding strip-metal knife mounted in said slot, and means for forcing the work against said knife in a progressive cutting action. 110

4. In a cutter for sheet material, the combination of a knife holding member, a flexible knife mounted and laterally supported therein, means for rigidly anchoring one end of said knife, means for yieldingly anchoring the other end thereof, and a roll adapted to press the work against said knife progressively from its rigidly anchored end toward its yieldingly anchored end. 115

5. In a cutter for sheet material, the combination of a knife-holding member formed with a knife-receiving slot having substantially uniform width throughout its knife-receiving region, an upstanding, strip-metal knife slidably mounted in said slot, means for rigidly anchoring one end of said knife, 120

130

- means for retaining the rest of the knife in said slot while permitting it to elongate and contract therein, and means for forcing the work against knife in a cutting action progressing from the rigidly anchored end toward the yieldingly anchored end of said knife.
6. In a cutter for sheet material, the combination of a knife-holding drum, an upstanding, strip-metal knife helically wound upon said drum, means on said drum for laterally supporting said knife, yielding means for holding said knife under longitudinal tension, and means for forcing the work 15 against said knife in a progressive cutting action.
7. In a cutter for sheet material, the combination of a knife-holding drum, a flexible knife helically wound thereon, yielding 20 means for holding said knife under longitudinal tension, and means for forcing the work against said knife in a progressive cutting action.
8. In a cutter for sheet material, the combination of a knife-holding drum, helically disposed knife-holding means on said drum formed with a knife-receiving slot having substantially uniform width through its
- knife-receiving portion, an upstanding, strip-metal knife mounted in said slot, and 30 means for forcing the work against said knife in a progressive cutting action.
9. In a cutter for sheet material, the combination of a knife-holding drum, a flexible knife helically mounted and laterally supported thereon, means for rigidly anchoring one end of said knife, means for yieldingly anchoring the other end of said knife, and means for forcing the work against said 35 knife in a cutting action progressing from 40 its rigidly anchored end toward its yieldingly anchored end.
10. In a cutter for sheet material, the combination of a knife-holding drum, an upstanding, strip-metal knife helically wound 45 upon said drum, means on said drum for laterally supporting said knife, means for rigidly anchoring one end of said knife, yielding means for anchoring the other end of 50 said knife, and means for forcing the work against said knife in a cutting action progressing from its rigidly anchored end toward its yieldingly anchored end.

In witness whereof I have hereunto set my hand this 12th day of April, 1924.

JOHN R. GAMMETER.
